CLAIM

D12/183; D14/126, 374
CPC G09F 3/02; G09F 3/203; G09F 7/00; G09F 7/12; G09F 7/14; G09F 7/16; G09F 2007/122; G09F 9/00; G09F 13/00; G09F 13/18; G09F 13/22; G09F 2013/1895; G09F 15/00; A45D 42/24

The ornamental design for a circular electronic screen/display with suction cups for motor vehicles and wearable devices, as shown and described.

See application file for complete search history.

DESCRIPTION

(56) **References Cited**

FIG. 1 shows a perspective view of a circular electronic screen/display with suction cups for motor vehicles and wearable devices.

U.S. PATENT DOCUMENTS

FIG. 2 shows the front view of a circular electronic screen/display with suction cups for motor vehicles and wearable devices.

65,871 A 6/1867 Browne
168,063 A 9/1875 Taylor
175,399 A 3/1876 Wheldon et al.
175,733 A 4/1876 Myers et al.
176,714 A 4/1876 Vanhon
260,332 A 6/1882 Simonson
740,330 A 9/1903 Luther
761,601 A 5/1904 Oscar
D39,680 S 12/1908 Henby

FIG. 3 shows the back view of a circular electronic screen/display with suction cups for motor vehicles and wearable devices.

FIG. 4 shows a side view of a circular electronic screen/display with suction cups for motor vehicles and wearable devices.

FIG. 5 shows the top view of a circular electronic screen/display with suction cups for motor vehicles and wearable devices; and,

FIG. 6 shows the circular electronic screen/display with suction cups mounted in a rear window of a motor vehicle. In the drawings, the broken lines illustrate environment and form no part of the claimed design.
